the invention, and certain variations and improvements will be apparent to those skilled in the art. It is to be understood, however, that the invention is not limited to the specific details of construction, materials, dimensions, proportions, arrangement, and the like, which have been described and illustrated, but is intended to cover all such modifications and changes as fall within the spirit and scope of the invention, as hereinafter set forth.

UNITED STATES PATENT OFFICE

2,381,290

SINGLE-ROW SCOUR PREVENTION FENCE

Thomas M. Joyce, Salinas, and Preston L. Fite, Sacramento, Calif.; said Thomas M. Joyce, deceased, assignor by decree of court to Teresa O. Joyce

Application October 31, 1941, Serial No. 417,302

3 Claims. (Cl. 61—3)

This invention relates to means for controlling stream erosion, and particularly to a single row scour prevention fence which may be arranged to cause sedimentary deposits in desired areas.

Control of the erosive action of running water is of prime importance along stream banks, highways, bridge approaches, and similar locations. Flood action causes unlimited damage to arable lands and to other property in its path. Protection from such danger has been largely accomplished through setting up of bulkheads, dikes, and the like which substantially prevent the flowing water from coming in contact with the areas to be saved. Such means have been very expensive, and open to numerous practical objections aside from the cost.

Our present improvement is concerned with a protective structure, which can be set up at a fraction of the cost of the previous types, and which will not only prevent the scouring out of a certain area, but can be used to cause a filling in of areas previously eroded away.

More specifically, our invention lies in the use of a single row scour prevention fence which is adaptable to varying conditions of stream flow and amounts of material carried in suspension, and which can be set up to induce sedimentation where necessary. It is especially suited to use along streams of the type prevalent in the western states, which may be dry, or substantially so, in the summer, and carry a maximum volume of water during the winter. The illustrated embodiments may be used in conjunction with many of the standard installations now in use, such as flexible rock and wire mattresses or articulated blocks which act as a protective layer to prevent undermining.

Our improvements may be used in place of double fencing now in use, which requires a fill between the fences, and offers important advantages over such prior art forms, as sacked concrete walls, sheet piling, pile revetments, concrete or asphalt slope paving, tetrahedrons, jackstraws, double pile fencing, and other means well known in the current practice.

The objects of our invention thus include: protecting arable lands, highways, bridge footings, and the like from the scouring action of running water; causing the depositing of material carried in suspension to replace eroded banks or to fill in desired areas; controlling the direction of stream flow; confining a stream effectively to a desired channel; preventing the shifting of stream beds from one location to another; reducing the expense of maintaining highways; re-

ducing the cost of stream control; simplifying the structural elements required to control a stream; eliminating the necessity for building solid dikes, jetties, or revetments to protect stream banks; and in general providing stream control means at a substantially lower cost than has hitherto been possible.

These and other objects will be apparent to those skilled in the art from the detailed description hereinafter. We reserve the right to make such changes in the exact form of the embodiments illustrated as may be necessary to provide maximum effectiveness in applying the principles of our invention to any particular situation. All such changes are deemed to lie within the scope of our invention.

The details of our invention will be better understood by reference to the drawing, in which:

Fig. 1 shows a perspective view in elevation of a protective fence embodying the principles of our invention;

Fig. 2 is a fragmentary sectional top view showing an alternative form of buffer for use in the embodiment of Fig. 1;

Fig. 3 is a schematic view illustrating preferred locations for the use of the different embodiments of our invention.

In our invention, we prevent erosion and promote sedimentation by introducing obstacles into a moving stream which cause eddies and velocity changes. When the main current of the stream is broken up, its power to wash away a bank is reduced. Whenever its velocity is reduced abruptly, or its direction changed, some of the material carried in suspension is deposited out. We have found this to be an effective method of preventing the carrying away of material, with the additional advantage of promoting filling action. As compared with a double row of fencing between which a fill of relatively large rock is made, our single line fencing is equally effective, at an installation cost of only from 20% to 40% of that required hitherto.

The matter of cost is of great importance in such work, and our invention makes possible adequate protection in many cases where the expense has hitherto been prohibitive, as well as the reclamation of many areas which could not otherwise be justified economically.

The advantages and features of our invention will be more fully understood by inspecting the drawing, in Fig. 1 of which we have shown a preferred form of our invention. A single row scour prevention fence, indicated generally as 1, is formed by fixing a number of posts 2 in the ground

3. The posts 2 must be set into the ground for a substantial proportion of their length to provide adequate support for a plurality of cables 4 which are fixed thereon.

We have illustrated our posts 2 as being made of wood, but metal or concrete may be used as well, and in many cases it is desirable to use sections of railroad rail. The cables 4 are fixed to the posts 2 by any suitable means. For example, staples 5 may be employed when wooden posts are used. Each of cables 4 is doubled, or composed of two separate strands 6 which are secured together at their point of attachment to posts 2, but are spread between adjacent posts for the insertion of buffers 7. Buffers 7 have been illustrated 15 as of rectangular cross-section, with their longer cross-sectional dimension normal to the main line of the fence 1. The buffers 7 could, however, be of any other shape which tends to interfere with the smooth flow of a stream and which will promote turbulence as, for example, triangular.

The buffers need not be set vertically, but could be mounted diagonally if desired, and could be set with their longer cross-sectional dimension parallel to the fence line, or at any other desired angle thereto. Staples 5 have been shown to secure the buffers to the cable strands 6, although any equivalent means may be substituted therefor. The buffers 7 are preferably set into the 20 ground, so that they are in part self supporting, and in part carried by the cables 4.

Fig. 2 shows a fragmentary section of fence of the type of Fig. 1, utilizing such triangular buffers 9. Buffers 9 are preferably inserted with one of their sides 10 facing upstream. The material used for the buffers may be wood, metal, brush, canvas, or anything which will resist the pressure of the stream flow. It is to be understood that the single 25 row of posts may be either straight or in curved or staggered array.

We have found that a single row scour prevention fence of the types shown in Figs. 1 and 2 will cause a sedimentary fill to develop in the course of a year or two at a distance behind the fence of several feet, gradually filling up to the fence line as a solid bank. The length of time required is dependent, of course, on the stream velocity, the size of the fence mesh, the amount of material carried in suspension by the stream, 30 and similar factors.

The diagram of Figure 3 illustrates typical locations in which scour prevention fences constructed according to the present invention may be employed advantageously. Along scour areas 35 50 and 51 fences according to the instant invention may be utilized both as protection against

further erosion and to promote replacement of the material already scoured out. These areas are typical of many in which further erosion might cause the loss of the approaches to bridge 52 or the washing out by stream 53 of a strip of highway 54. Substantial areas of arable land may be reclaimed by filling-in of areas such as those shown at 50 and 51. At 55, where the stream bank paralleling highway section 56 which is in danger of being undercut and destroyed by stream 53, scour prevention fences of the types described herein may also be used with beneficial results, particularly if backfill material is added immediately.

Summarizing, we have developed a form of protection against erosion which is very advantageous economically, and which is superior in causing sedimentary deposits, thus replacing previously scoured out areas. Our invention is equally useful in confining stream currents to desired channels, and thus preventing the shifting of stream beds. The cost of our single row structure is so little compared with existing types that it is possible to reclaim arable lands and to insure protection of property in cases where the expense would otherwise seem prohibitive.

What we claim is:

1. The combination in a stream control device of a single row of retaining posts and flexible buffer means between said retaining posts, said means including a plurality of cables fixed between said posts and a plurality of upright buffer members having a generally rectangular shape fixed to and between said cables with their shorter cross-sectional dimension disposed parallel to the direction of stream flow.

2. The combination in a stream control device of a single row of retaining posts and flexible buffer means between said retaining posts, said buffer means including flexible securing means fixed between said posts and a plurality of upright buffer members having a generally polygonal cross-sectional shape fixed to and between said flexible securing means with their shorter cross-sectional dimension disposed approximately parallel to the direction of stream flow.

3. The combination in a stream control device of a single row of retaining posts and flexible buffer means between said retaining posts, said buffer means including flexible securing means fixed between said posts and a plurality of upright buffer members having a generally rectangular shape fixed to and between said flexible securing means with their greatest width approximately at a right angle to the line of said retaining posts.
